Couns.

UNITED STATES PATENT OFFICE.

ROBERT E. FRUIN, OF CHICAGO, ILLINOIS.

CUSHION-TREAD HORSESHOE.

Application filed September 3, 1927. Serial No. 217,318.

This invention relates to horseshoes, and has reference more particularly to a well-known type known as cushion-tread shoes wherein the under side of the shoe frame is equipped with a rubber pad to soften the impact of the shoe on the pavement.

A large variety of horseshoes of this type has heretofore been proposed and disclosed in Letters Patent and other literature on the subject, and many of such shoes have gone into extensive use. In one type of cushion-tread shoe, which has met with considerable favor, the cushion pad has been formed in its lower or under surface with one or more cavities or cups designed to afford a suction effect, under the squeezing and partial flattening of the yieldable cushion on the ground, and thereby give a more sure foothold and lessen the danger of slipping, on the same principle by which a rubber hemisphere, if pressed down on a smooth surface and the contained air partially squeezed out around its edges, clings to the surface. However, in many shoes of this vacuum-cup type with which I am acquainted, the cup or cups have heretofore been too small to have much suction effect, or their walls have not been of equal and uniform height so as to afford continuous contact with the ground or pavement at all points on their edges. Furthermore, many of these vacuum or suction cups have heretofore extended only partially through the pad, and not entirely therethrough, thus limiting the ventilation of the frog portion of the animal's hoof to such small amount of air as may find its way in through the rear of the hoof above the upper rear portion of the shoe. Of course, in many cushion-tread shoes, the frame of the shoe has been equipped with an open pad covering the front and side portions of the frame but not extending across the gap at the heel; but of course such shoes are in no sense vacuum-cup shoes, since the gap at the heel of the shoe prevents any suction effect.

In another known type of cushion-tread horseshoe, the bottom of the shoe frame has been formed with a continuous slot or channel in its side, toe and heel portions in which is fitted a cushion pad, the latter in some instances including an integral heel portion

bridging the rear ends of the shoe frame. My present invention relates to this type of shoe, and has for its main object to provide an improved construction providing better 55 wearing qualities and greater durability, maximum suction, and hoof-ventilating effects, lessened liability of "balling", and more perfect anchorage of the pad on the frame.

I have also found that a very durable construction of cushion pad is obtained by providing a wide heel portion with a flat bearing surface in association with a semi-oval side and toe portion of considerably less width and formed with a transversely convex or 60 rounded bearing surface which, of course, is more or less flattened when under weight, the transversely rounded or generally rope-like form of the said side and toe portion being less liable to be cut and frayed by the edges 65 of the walls of the containing channel or groove in the frame than where said side and toe portion has a flat bearing surface more or less overhanging said edges.

Still other objects and attendant advantages of the invention will be apparent to persons skilled in the art from the following description, taken in connection with the accompanying drawing wherein I have illustrated a preferred embodiment of the invention, and in which—

Fig. 1 is a bottom plan view of the metal horseshoe frame;

Fig. 2 is a similar view of the same, with the cushion pad applied thereto; and

Figs. 3, 4, and 5 are cross-sections taken on the lines 3—3, 4—4, and 5—5, respectively, of Fig. 2.

The frame of the shoe, best shown in Fig. 1 and designated as an entirety by 10, is a metal 90 forging having the usual horseshoe outline form. In the forging operation the metal is so distributed as to form on the bottom of the frame a continuous inner wall 11 bordering the inner edges of the toe and side portions 95 of the frame, outer side walls 12 opposite to and parallel with the side portions of the inner wall 11, outer side walls 13 bordering the outer and rear edges of the heel portions 100 of the frame and connected with the rear ends of the walls 12 by oblique connecting walls 14, and a forwardly offset outer toe wall 15 be-

tween and continuous with the outer side walls 12. The outer side walls 12 are higher than the inner wall 11, as shown in Fig. 4, and are set inwardly from the outer side edges 5 of the frame to provide space for the usual nailing holes 16, while the offset tip or toe wall 15 of substantially the same height as the side walls 12 borders the outer front edge of the frame. The described disposition of 10 the walls 11, 12 and 15 creates between them a continuous narrow channel or groove 17, having a central widened toe portion 17' between the walls 11 and 15. The walls 13 and 14 and the rear end portions of the walls 11 15 form between them widened rear or heel extensions 17^a of the channels 17 that constitute 20 pockets for the end portions of the rubber heel pad 18 that bridges across the rear ends of the frame, there being gaps between the 25 rear ends of the walls 11 and 13 through which the heel pad 18 extends. The bottoms of the pockets 17^a are formed with holes 19 through which the rubber of the pad 18 is forced, before vulcanization, and spread on 30 the upper face of the frame, as shown at 20 in Fig. 5, to key the heel pad in place.

Continuous at its rear ends with the end portions of the heel pad 18 and occupying the channel 17 and its widened portion or 35 pocket 17' is a semi-oval side and toe pad, the side portions 21 of which, filling the channels 17, are of oval form in cross-section, as shown in Fig. 4, the toe portion 21' being somewhat widened at its base to fill the toe pocket 17' 40 of the frame, as shown in Fig. 3. The bottom or wearing surface of this side and toe pad is flush and in the same flat plane with the bottom or wearing surface of the heel pad 18; and since the wearing surfaces of the two 45 pads are continuous, a large central vacuum or suction cup is formed extending through both the frame and the annular rubber cushion on the bottom of the frame, and all points on the wearing surface or rim of this 50 vacuum cup are pressed into contact with the flat surface of the pavement or roadway, so that under normal conditions a strong anti-slipping suction effect is secured. In mud or snow, of course, the opening becomes more or 55 less filled and packed, but in such a case the large size of the opening and the downwardly and outwardly flaring form of its walls facilitate the discharge of the packed-in material when the animal's hoof is raised from the 60 ground. Also, the transversely rounded form of the side and toe portions of the pad prevents the cutting and fraying of the rubber on the edges of the channel walls as the 65 pad is compressed, and thus increases the durability and life of the shoe. Since in service there is greater outward than inward side thrust on the portions 21 of the pad, the outer walls 12 are advantageously made somewhat higher than the inner wall 11.

65 In the manufacture of the shoe, an annular

pad of raw rubber possessing roughly the size and form of the finished pad is laid on the channeled side of the shoe frame, and the frame and pad are then tightly clamped in a vulcanizing mold, one face of which is shaped to an impression of the bearing surface of the pad so that under the squeezing action of the mold the pad is given its final or finished form; and the mold is then placed in the vulcanizing oven. The pad is strongly united 70 to the frame by a well-known treatment which consists in first dipping the frame in a copper sulphate solution, which deposits a copper film on the frame that acts as a binding medium for the rubber and the metal. As shown in Fig. 2, the wearing surface of 75 the heel pad 18 is preferably roughened or corrugated, as indicated, but this feature is well-known in the art and forms no part of 80 the present invention.

85 I claim—

1. In a cushion-pad horseshoe of the type described, the combination of a metal shoe frame formed with a channel on its under side, said channel having widened heel and toe portions, a wide heel pad seated at its ends in said widened heel portions of the channel and bridging the rear ends of said frame, said heel pad having a flat wearing surface, and a narrow semi-oval side and toe pad seated in 90 the side and toe portions of said channel, said side and toe pad formed with a transversely convex ground-engaging portion projecting below said channel with its wearing surface continuous and flush with the wearing surface of said heel pad.

2. In a cushion-pad horseshoe of the type described, the combination of a metal shoe frame formed on its under side with an inner wall bordering the inner edge thereof and a higher outer wall having laterally offset toe and heel portions, said inner and outer walls forming between them a channel having widened heel and toe portions, a wide heel pad at its ends filling said channel heel portions and bridging the rear ends of said frame, said heel pad having a flat wearing surface, and a narrow semi-oval side and toe pad filling the side and toe portions of said channel, said side and toe pad formed with a transversely convex ground-engaging portion projecting below said channel with its wearing surface continuous and flush with the wearing surface of said heel pad.

3. In a cushion-pad horseshoe of the type described, the combination of a metal shoe frame formed on its under side with an inner wall bordering the inner edge thereof and terminating short of its rear end and a higher outer wall having a forwardly offset toe portion and outwardly offset heel portions bordering the rear outer side and end portions of said frame, said inner and outer walls forming between them a channel having widened heel and toe portions, the bottoms of said heel por-

tions having apertures, a wide heel pad at its ends filling said channel heel portions and anchored thereto through said apertures and bridging the rear ends of said frame, said heel
5 pad having a flat wearing surface, and a narrow semi-oval side and toe pad filling the side and toe portions of said channel, said side

and toe pad formed with a transversely convex ground-engaging portion projecting below said channel with its wearing surface continuous and flush with the wearing surface of
10 said heel pad.

ROBERT E. FRUIN.
